US00D817170S

(12) **United States Design Patent** (10) **Patent No.:** **US D817,170 S**
(45) **Date of Patent:** **** May 8, 2018**

(54) **LID**

(71) Applicant: **YETI Coolers, LLC**, Austin, TX (US)

(72) Inventors: **Roy Joseph Seiders**, Austin, TX (US);
Derek G. Sullivan, Austin, TX (US);
Andy Bondhus, Austin, TX (US); **Evan Goldberg**, Austin, TX (US)

(73) Assignee: **YETI Coolers, LLC**, Austin, TX (US)

(**) Term: **15 Years**

(21) Appl. No.: **29/568,695**

(22) Filed: **Jun. 20, 2016**

(51) LOC (11) Cl. **09-07**

(52) U.S. Cl.

USPC **D9/449**; D7/396.2

(58) **Field of Classification Search**

USPC D3/294, 295; D7/213, 387, 392, 392.1,
D7/396.1, 396.2, 396.3, 541, 546, 549,
D7/554.2, 554.3, 602, 605, 701, 703, 705;
D9/414, 420, 426, 428, 430, 434-436,
D9/438, 443, 449, 454, 455, 499, 703,
D9/717, 721

CPC B65D 47/122; B65D 47/2037; B65D
2581/3447

Primary Examiner — Robert M Spear

Assistant Examiner — Darcey E Heflin

(74) Attorney, Agent, or Firm — Banner & Witcoff, Ltd.

(57) **CLAIM**

The ornamental design for a lid, as shown and described.

DESCRIPTION

FIG. 1 is a top, front, right perspective view of a lid showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top, front, right perspective exploded view thereof;

FIG. 9 is a front exploded view thereof;

FIG. 10 is a rear exploded view thereof;

FIG. 11 is a right exploded view thereof;

FIG. 12 is a left exploded view thereof;

FIG. 13 is a top exploded view thereof; and,

FIG. 14 is a bottom exploded view thereof.

The claim is defined by the shaded surfaces. In the drawings the broken lines showing portions of the lid depict environment and form no part of the claimed design.

1 Claim, 11 Drawing Sheets
